NONMETALLIC BOTTLE CAP

Serenus H. A. Young, St. Paul, Minn., assignor to
 Young Engineering Laboratories, Inc., Minneapolis, Minn., a corporation of Minnesota

Application January 15, 1937, Serial No. 120,717

4 Claims. (Cl. 215—38)

My invention relates to an improvement in bottle caps of a type particularly designed for use in covering milk bottles and the like. My cap is provided with a skirt portion adapted to extend down over the pouring lip of the bottle. Plaits or folds are provided in this skirt portion to restrict the diameter thereof, and to cause this portion to fit closely about the pouring lip of the bottle.

It is an object of my invention to provide a cap formed of paper or other suitable material, having a coating thereon of a material capable of acting as a bonding agent. This bonding agent is capable of adhering to itself or among other surfaces, to those which have a wax coating or impregnation, or to paper surfaces. This coating permits the skirt of the cap to be folded in a series of plaits which remain in folded form when once folded for locking the cap securely in position on the bottle without adhering the cap to the bottle.

It is an object of my invention to provide a series of tabs forming the skirt portion of the cap. These tabs are ordinarily connected by folds and overlap to some extent. The bonding agent within the folds tends to hold the folds in closed position. However, in order to seal the folds closed, a portion of each fold between overlapping tabs is cut away to permit the overlapping portion of one tab to seal directly to the tab overlapped.

In the past pressure sensitive adhesives, temperature sensitive adhesives, and water soluble adhesives have been used for sealing purposes. Pressure sensitive adhesives however, are normally tacky and can not well be used on caps which must be contained in superimposed relationship. Furthermore, such tacky adhesives foul the bottle top making cleaning of the bottles difficult. Where temperature sensitive adhesives are used, the folds must be held in folded position by some physical means until the adhesive temperature drops sufficiently to solidify the same. Where water soluble adhesives are used, the caps adhere to wet surfaces such as the pouring lip. Furthermore, the high moisture content of the milk would soften such adhesives used on bottle caps. Each of the adhesives formerly used accordingly possess undesirable qualities.

It is the purpose of my invention to provide a thermoplastic coating formed by combining rubber and wax in suitable proportions. The cap provided with such a coating composition will readily seal in the presence of moisture to lock

the bottle cap in position. When this composition is used, the cap may be applied by pressure or temperature, or by a combination of both. The bonding agent is not tacky at normal temperatures and will not crack or separate itself from the base material of the cap when it is folded 180° into plaits. As such material is not moisture absorbent the formation of a plug or pad of cream on the cap will be avoided. The coating will also act as a gasket to prevent leakage of moisture.

These and other objects and novel features of my invention will be more clearly and fully set forth in the following specification and claims.

In the drawings forming a part of my specification:

Figure 1 is a perspective view of my milk bottle cap in position on the top of a bottle.

Figure 2 is a plan view of the blank from which my cap is formed.

Figure 3 is a plan view of a modified form of blank construction for forming a slightly different type of blank.

Figure 4 is a plan view of a modified form of blank construction.

Figure 5 is a plan view of another modified form of blank.

Figure 6 is a side elevation view of a blank having a plug cap adhered to the upper surface thereof.

Figure 7 is a view similar to Figure 6 showing a plug cap adhered to the lower surface of a cap blank.

Figure 8 is an enlarged section illustrating the manner in which the coating on the inside face of the cap acts as a gasket between the cap and surface on the bottle.

Figure 9 illustrates a side view of a blank before the coating is added thereto.

Figure 10 illustrates the blank shown in Figure 9 having a coating of suitable thermoplastic composition on one side thereof.

Figure 11 illustrates the blank shown in Figure 9 impregnated with wax on either side thereof.

Figure 12 discloses the wax impregnated blank of Figure 11 having a surface coating of thermoplastic composition thereon.

Figure 13 illustrates a blank as shown in Figure 9 with an adhesive coating on one side thereof and a wax impregnated surface on the other side of the same.

Figure 14 discloses a cap blank having a surface of suitable thermoplastic composition on either side thereof.

Figure 15 illustrates a blank formed as shown

in Figure 12 having a coating of dusting material on the thermoplastic coating thereof to prevent adhering of superimposed blanks.

Figure 16 illustrates in section, my cap as formed in readiness for being applied to a bottle.

Figure 17 illustrates my cap in cross-section applied to a bottle.

Figure 18 illustrates in section my cap of the type disclosed in Figure 7 applied to a bottle.

Figure 19 illustrates a cap of slightly different form applied to the neck of a bottle.

Figure 20 illustrates in enlarged form, the manner in which the tabs forming the cap are adhered together.

15 My cap A is formed of a blank of prepared paper or the like. This blank 10 is formed as illustrated in Figure 2 of the drawings. The blank 10 is substantially circular in shape, and comprises a central bottle mouth covering portion 11, and a skirt 12 adapted to be folded with a series of plaits over the pouring lip of the bottle B. In the preferred form illustrated in Figures 1 and 2, the plaits are formed by a series of equally spaced fold lines 15 and 18, which 20 do not extend radially, but extend so that each line, if extended, would be tangent to a circle 13 concentric with the cap blank 10. A notch 14 is provided adjacent each of the fold lines 15, at the lower end of each pleat 17 this notch 14 being at its widest point a width equal to the 25 difference between the actual width of the blank between plaits at this point, and the width of an equal angular segment of the bottle neck at this point.

30 35 In other words, the fold lines 15 and 18 divide the blank into a series of segments 19 and pleats 17. At the outer extremity of the blank, these segments are substantially wider than necessary to encircle the bottle at the base of the rim or bead 16 thereof. The skirt portion 12 of the cap 10 must be plaited or folded to fit tightly against the bottle. The notches 14 extend the width of the pleats 17 between the fold lines 15 and the fold lines 18. The outer extremity of each segment 19 is cut to provide a continuous circular line 16 about the bottle when the cap is in proper sealed position as shown in Figure 1.

When the cap A is in place upon the bottle B, the segments are wrapped spirally down over the 50 bottle pouring lip and rim of the bottle, this spiral wrapping assisting in keeping the segments smooth. The folds 17 adhere together in a manner which will be later set forth in detail, the notches 14 permitting the inner surface of a portion of each segment 19 to directly contact a portion of the outer surface of the next adjacent segment.

55 In Figure 3 I illustrate a blank for a cap C being substantially similar in shape to the blank of the 60 cap A. This cap is provided with a central mouth covering portion 20 and a skirt portion 22. The skirt 22 is provided with a series of radially extending fold lines 27 extending to the outer periphery of the blank. The skirt between the fold lines 27 is divided into a segment portion 24 and a pleat portion 25, the pleat portion 25 being bounded by fold lines 27 on the sides. Notches 28 extend the width of the pleat portions 25 to permit a portion of the inner surface of each 65 segment portion 24 to contact directly the corresponding portion of the outer surface of the next adjacent segment portion 24. In this construction, additional fold lines or corrugations 29 may be provided centrally in each segment portion 24 to compensate for any excessive paper

at the point where the cap extends over the pouring lip of the bottle B. These folds 29 act to reinforce the cap, and act as leader plaits to cause the folding of the paper along these lines when the central portion of the cap is drawn into the 5 neck of the bottle.

Figure 4 shows a slightly different form of construction. In this figure, a blank for a cap D is provided having a central bottle mouth covering portion 30 and a skirt portion 32. The skirt 32 is 10 folded to provide a series of segments 33 and a series of connecting plaits 34, bounded by fold lines 35 and 36. Openings 37 are provided through the folds or plaits 34 to permit the inner surface of one segment to contact a portion of 15 the outer surface of the next adjacent segment 33.

In the usual form, the blank, such as 10 is provided with a plug cap 38 adhered to one surface thereof to seal the top of the bottle. The cap 38 may be adhered to the upper surface of the cap 20 blank, as illustrated in Figure 6, or may be secured to the bottom thereof, as shown in Figure 7.

The blank 10 is provided with a coating of a suitable thermoplastic composition 40 as illustrated 25 in Figure 10 of the drawings.

In preparing the paper for formation of the cap blank, wax or other waterproofing material is usually impregnated into both surfaces of the blank, as shown in Figure 11 of the drawings. Upon this blank having wax impregnation 39 therein, I provide a coating 40 of thermoplastic sealing material. This material is formed of a composition which will be later described which will seal to the bottle only under elevated temperature or pressure.

As the film coating of thermoplastic composition will adhere to waxy surfaces, it may be only desirable to coat one side of the paper with the thermoplastic composition film if the paper is 40 impregnated with wax. Figure 12 shows a wax impregnated paper having a coating of the thermoplastic composition film on one side only. This film could just as well be on both sides in this form. Figure 13 shows a film coating on one side of a paper, with a wax impregnation on the other side. Figure 14 shows a paper coated with the thermoplastic composition film on both sides. In Figure 15 the paper is impregnated with wax and is provided with a thermoplastic composition film of coating. A protective coating of starch, flour, or other harmless material may be provided, as at 42, to prevent adherence between adjacent caps when stacked or nested in large piles, or in case abnormal temperatures are experienced in some manner between the manufacture of the caps and the use thereof.

The construction of the cap may be seen from Figures 16 and 17 of the drawings. Figure 6 60 shows a coated sheet 10 from which a cap such as A, C or D is to be made. Figure 6 shows a sheet 10 having a plug cap 38 adhered to the upper surface thereof. Figure 16 shows the cap A in section in partially formed state in which 65 it is made and shipped for use in the capping operation. In this figure in dotted outline may be seen a series of superimposed caps A, showing the manner in which the caps may be stacked. The skirt portion 12 of the cap A is projecting 70 downwardly from the central portion 11 thereof in a truncated conical formation, and the plaits or folds are in partially folded position.

In Figure 17 the cap A is shown in section in engagement with the top of a bottle B. The 75

central portion 11 extends over the top of the bottle and into the bore or mouth of the bottle 44. To reinforce the central portion 11, the plug cap 38 adhered to or stapled to the center of the blank 5 extends within the bore or mouth 44, acting to hold the central portion of the blank in position. The skirt 12 is wrapped tightly about the rim 16 of the bottle B, the skirt being formed in a series of plaits or folds as described. Each segment 19 10 overlaps the next adjacent tab and is adhered thereto, in the manner illustrated in Figure 1, and in enlarged form in Figure 20. When in this position, the coating on the under surface of the blank forms a tight seal against the bottle acting 15 as a gasket in the manner illustrated in Figure 8.

A similar construction is shown in Figure 18, with the exception that the plug cap 38 is formed on the under side of the blank, rather than on the top side. With this exception, the caps of Figures 17 and 18 are alike.

Figure 19 is similar to that of Figures 17 and 18, but in this figure the blank is stretched taut across the top of the bottle, and no plug cap such as in Figures 17 and 18 is used. In the construction of Figure 19, the folds hold the cap upon the top of the bottle, and the thermoplastic composition film on the inside of the cap provides a gasket for the sealing of the cap upon the bottle top.

The cap illustrated in Figure 5 differs from the other caps in that it is provided only with an annular ring of bonding material 77 extending peripherally about the same. This cap is formed in a series of segments 78 in the skirt 79, each segment being bounded by a substantially radially extending line 80 and a projecting portion 82 which is formed to overlap the next adjacent segment and to adhere thereto.

The coating of thermoplastic composition which I have described to some extent, is preferably formed of paraffin wax and rubber as disclosed in U. S. Patent No. 2,054,112 and No. 2,054,113. The paraffin wax has a melting point between 120 and 140° F. and comprises from 70 to 94% of the solution. The rubber used may include india rubber or Hevea rubber, gutta rubber, and their natural or synthetic equivalents for the purpose of this invention, singly or mixtures thereof. The term "india-rubber" may include pale crepe rubber, smoke sheet rubber, synthetic rubber, artificial gummy substances and polymers. The term wax may include the use of paraffin wax, beeswax, spermaceti, candelilla, carnauba, amorphous waxes and other natural or synthetic waxes.

In forming the adhesive, the wax is melted by heating to a temperature of from 180° F. to 220° F. The rubber is then added in small pieces torn from thin sheets or in a shredded or otherwise subdivided form. The addition of the rubber reduces the temperature which should be allowed to drop to around 180° F. and thereafter be maintained between 160 and 180° F. until the rubber is thoroughly dissolved. It is desirable to keep the temperature of the mixture at about the temperatures indicated, to avoid over heating which results in an undesirable darkening of the mass and an undesirable odor.

After the rubber has been in the paraffin wax 70 for about an hour, the pieces of rubber are sufficiently softened and swollen to permit complete disintegration by agitation. With an ordinary revolving blade stirrer, it requires 5 to 6 hours to produce a smooth solution of the rubber and paraffin wax, but with equipment especially de-

signed for this work the time can be materially reduced.

In compositions of this adhesive up to about 30% by weight of pale crepe rubber, at which percentage the viscosity becomes too great, the cohesiveness of the mixture and its adhesiveness 5 as a coating increase with the viscosity of the mixture. It is therefore important not to lower the viscosity of any given mixture unnecessarily as by increasing the temperature or time of heating of 10 the ingredients when dissolving the rubber in the paraffin wax. The viscosity for a given concentration of rubber in wax decreases with the time of heating.

Since a solution of rubber and wax have widely 15 varying viscosities and it is desirable to maintain a viscosity of not less than 8000 secs. (Scott viscosimeter at 90° C.), means may be provided to maintain or to vary the viscosity. The viscosity of rubber in wax decreases with the time of 20 milling the rubber used in the mixture. With the given concentration of rubber in wax very small percentages of a rubber accelerator, such as mercaptobenzothiazol, will markedly reduce the viscosity. The effect of this accelerator is dependent 25 upon the specific accelerator used and the percentage added. With a given concentration of rubber in wax, vulcanizing agents (such as sulphur chloride) reduce the viscosity. The addition of anti-oxidants, such as symmetrical dibeta- 30 naphthyl-p-phenylene diamine, has little effect on the viscosity.

Additional viscosity may be obtained in a paraffin wax mixture by the use of other materials than rubber, such as aluminum stearate, but the 35 resultant mixture is less effective as an adhesive and a moisture-proofing.

The minimum heat and time required to make a suitable heat seal with my composition will vary slightly with the composition of the mixture. If it contains, for example, 12% of pale 40 crepe rubber, it will seal in not over 3 seconds at a temperature of 300° F. to 500° F. depending upon the thickness of the paper to which the seal is being made. I have found that satisfactory seals 45 may be made at temperatures ranging from 200° F. to 500° F.

The thermoplastic composition thus provided has benefits of particular advantage for use on bottle caps. Thin paper coated with this material may be folded 180° F. without cracking or 50 breaking the waterproof film. The thermoplastic composition is readily removed by caustic cleaning solutions ordinarily used in creameries. Furthermore, the specific composition has an extremely important quality of adhering in the 55 presence of moisture. This last feature makes a construction which is decidedly advantageous over prior types of caps.

Milk bottles are ordinarily washed with hot 60 water and cleaning fluids and rinsed with cold water to cool the bottles before filling the same with milk. A small amount of water often remains on the outer surface of the bottle after rinsing. Furthermore, in filling the bottles, milk or cream is often spilled upon the pouring lip of the bottles. It is, therefore, apparent that there is often moisture on the surface of the bottles when the capping operation takes place. My composition will seal properly in the presence of this moisture. Often moisture is applied to the caps before the caps are put on the bottles in order to prevent too tight a seal between the cap and the bottle. In constructions where plug caps are used, the seal is mainly effected

by the central depressed portion of the cap. The moisture on the lip provides a control for the degree of sealing of the cap.

In accordance with the patent statutes, I have described the plans of operation and construction of my bottle cap and while I have endeavored to set forth the best embodiments thereof, I desire to have it understood that this is only a means of carrying out my invention and that obvious changes may be made within the scope of the following claims without departing from the spirit of my invention.

I claim:

15. A cap for bottles and other containers formed of light foldable sheet material, a coating of thermoplastic composition on the inner face of said cap adapted to be placed in contact with the mouth of a container, said cap having a central mouth covering portion and a skirt portion, a series of spaced substantially radially extending fold lines in said skirt portion adapted to enable same to form a series of segments and connecting pleats, a portion of each of said pleats being cut out thereby permitting a portion of the inner coated face of each segment to be folded over in direct contact with the corresponding portion of the outer surface of the next adjacent segment portion and to be adhered thereto by heat and pressure, and the inner coated face of each pleat being adapted to be folded over in direct contact with the corresponding inner coated surface of the next adjacent segment portion and adhered thereto by heat and pressure.
20. 2. A cap for bottles and other containers formed of a light foldable sheet material, a coating of thermoplastic composition on the inner face of said cap adapted to be placed in contact with the mouth of a container, said cap having a central mouth covering portion and a skirt portion, a series of spaced substantially radially extending fold lines in said skirt portion adapted to enable same to form a series of segments and connecting pleats, leader pleats positioned at the inner end portions of each segment, the lower end portion of said pleats being cut to form notches thereby permitting a portion of the inner coated face of each segment to be folded over in direct contact with the corresponding portion of the outer surface of the next adjacent segment portion and to be adhered thereto by heat and pressure, and the inner coated face of each pleat being adapted to be folded over in direct contact with the corresponding inner coated surface of the next adjacent segment portion and adhered thereto by heat and pressure.
25. 3. A cap for bottles and other containers formed of a light foldable sheet material, a coating of thermoplastic composition on the inner face of said cap adapted to be placed in contact with the mouth of a container, said cap having a central mouth covering portion and a skirt portion, a series of spaced substantially radially extending fold lines in said skirt portion adapted to enable same to form a series of segments and connecting pleats, the outer extremity of each segment being cut to provide a continuous circular line when the cap is sealed in position, the lower end portion of said pleats being cut to form notches thereby permitting a portion of the inner coated face of each segment to be folded over in direct contact with the corresponding portion of the outer surface of the next adjacent segment portion and to be adhered thereto by heat and pressure, and the inner coated face of each pleat being adapted to be folded over in direct contact with the corresponding inner coated surface of the next adjacent segment portion and adhered thereto by heat and pressure.
30. 4. A cap for bottles and other containers formed of a light foldable sheet material, a coating of thermoplastic composition on the inner face of said cap adapted to be placed in contact with the mouth of a container, said cap having a central mouth covering portion and a skirt portion, a series of spaced substantially radially extending fold lines in said skirt portion adapted to enable same to form a series of segments and connecting pleats, leader pleats positioned at the inner end portions of each segment, the lower end portion of said pleats being cut to form notches thereby permitting a portion of the inner coated face of each segment to be folded over in direct contact with the corresponding portion of the outer surface of the next adjacent segment portion and to be adhered thereto by heat and pressure, and the inner coated face of each pleat being adapted to be folded over in direct contact with the corresponding inner coated surface of the next adjacent segment portion and adhered thereto by heat and pressure.

SERENUS H. A. YOUNG. 50
